UNITED STATES PATENT OFFICE.

PATRICK KENNELLY, OF BRIDGEPORT, CONNECTICUT.

PROTRACTOR.

SPECIFICATION forming part of Letters Patent No. 285,907, dated October 2, 1883.

Application filed February 20, 1883. (No model.)

To all whom it may concern:

Be it known that I, PATRICK KENNELLY, a citizen of the United States, residing at Bridgeport, in the county of Fairfield, State of Connecticut, have invented an Improved Protractor, of which the following is a specification.

My invention relates to that kind of a protractor in which there is a revolving center 10 and a straight edge, whereby machinists and other artisans may use their plain bevel-square in determining the different angles.

The object of my invention is to provide a tool for accurately determining all angles, in 15 connection with the common bevel-square, which is a part of the usual outfit of all iron-workers.

In the drawings forming a part of this specification, Figure 1 is a plan view of the protractor graduated from ninety degrees at right angles to the base-line *a b* to *o* at each of the 20 ends which are parallel to the base-line, substantially as shown. Fig. 2 is an edge view of Fig. 1. Fig. 3 is an enlarged view of swivel-center. Fig. 4 is an enlarged cross-section of 25 Fig. 3, showing the upper portion cut to the center at *a*. Figs. 5 and 6 are a plan and elevation of screw for fastening Fig. 3 to Fig. 1, as shown in Fig. 2 at *b*.

To operate the device it is only necessary 30 to place one edge of the bevel-square on the

edge *a b*, Fig. 1, then bring the blade against the face of that part of Fig. 3 which is shown in cross-section at *a*, Fig. 4. It will then be found that the blade will stop in the center and register the angle accurately on either side of the perpendicular.

I am aware that prior to my invention protractors have been used by draftsmen and others; those, however, cannot be used by machinists, tool-makers, and a large class of other tradesmen, each of whom have a plain bevel-square, which, with the use of my invention, will enable them to use it to advantage; but I am not aware that any with a revolving self-adjusting center has been used; therefore I claim—

1. The combination of the revolving center, Fig. 3, the upper part of which is cut away to the center, as shown, and the graduated arc, 40 as and for the purpose described.

2. The combination of the graduated arc, Fig. 1, and self-adjusting center, Fig. 3, one-half of which is removed to the center, as shown at *a*, Fig. 4, with edge of Fig. 1, so that 45 the center will adjust itself to any angle desired, substantially as shown.

PATRICK KENNELLY.
